GEORGE LAWSON BALLARD, OF NORRISTOWN, PENNSYLVANIA, ASSIGNOR TO WILD-
MAN MFG. CO., OF NORRISTOWN, PENNSYLVANIA.

TAKE-UP MECHANISM FOR KNITTING-MACHINES.

940,656.

Specification of Letters Patent. Patented Nov. 23, 1909.

Application filed October 18, 1907. Serial No. 398,275.

To all whom it may concern:

Be it known that I, GEORGE LAWSON BALLARD, a subject of the King of England, residing at Norristown, Pennsylvania, have 5 invented certain new and useful Improvements in Take-Up Mechanism for Knitting Machines, of which the following is a specification.

It is the object of my invention to provide 10 a take up for knitting machines which may be applied either to the form of machine requiring a revolving take up, that is, one revolving with the knitting head or one which may be supported on the fixed frame, 15 said take up having take up rolls carried by pivoted arms and being thus of a gravity take up character, the action of said rolls and their pivoted arms however, controlling the pressure between certain friction sur- 20 faces at the drive to regulate the rotation of the rolls according to the requirements due to variations in the tension of the fabric passing from the needles.

The invention consists in the features and 25 combination and arrangement of parts hereinafter described and pointed out in the claims.

In the accompanying drawings, Figure 1 is a side elevation of my invention. Fig. 2 30 is a plan view of the bracket at one end of the take up rolls with the parts associated therewith. Fig. 3 is a front view of the hangers with the rolls in place and showing also the driving mechanism. Fig. 4 is a 35 view of a detail part.

The take up rolls 1, 1, are journaled in arms 3 which are fixed by set screws 4 to a rod or shaft 5 journaled in standards 6, 7, at 8. The said standards 6 and 7 may de- 40 pend from the rotary knitting head and at their lower ends they have attached thereto the take up ring, well known in this art. The center of the said shaft, or in other words the pivot point of the arms, which 45 support the take up rolls, is at or very close to the plane of the point where the worm 9 and worm wheel 10 mesh with each other. The worm wheel is on the shaft of one of the take up rolls and the worm 9 is on the drive 50 shaft 17 and is driven therefrom through friction members 20—22 hereinafter referred to, associated with the drive shaft 17.

One of the arms of the pivoted frame made up by the said arms 3 and their cross 55 shaft 5, is connected by a link 11 with a

lever 12, pivoted to a bracket 13 at 14, said bracket being fixed to the hanger or standard 6. This lever has an adjustable screw 15 bearing on the rod 16, which passes down through the hollow upper end of the vertical drive shaft 17, to which power is applied from the rotary motion of the knitting machine. For this purpose the said shaft is provided with a gear wheel 17* which meshes with a circular rack, not shown, on the fixed frame and thus rotates the drive shaft 17 as the whole take-up mechanism revolves with the knitting machine.

The pin 16 has a key 18 extending through slots 19 in the vertical shaft 17 and through slots in the hub of the upper friction drive member 20. This key serves to exert a downward pressure on the friction member 20 as the lever 12 is subjected to a downward stress due to its spring 12* and the weight of 75 the rolls 1. When so pressed upon the friction clutch member 20 presses harder upon the lower clutch member 22, which is connected to the driving worm 9 through the hollow stem portion 22* and thus the take-up rolls will be driven with greater power. The spring 12* for pressing the lever is arranged in a boxing or bracket fixed to the standard 6 and is adjusted by a screw 23. The screw is held in its adjusted position by 80 a pin 24 which is pressed by a spring 25. The worm 9 is loose on the drive shaft. A spring is arranged at 26 upon which the pivoted frame or arms rest to sustain the weight thereof and provide a resilient cushion.

When the take-up is working normally, the spring is adjusted to set the parts of the friction drive under such pressure as to cause the take-up rolls to take care of the fabric as it is produced normally. If, however a heavy welt arrives at the take-up rolls and will not go through immediately, then the moment this occurs the arms upon which the take-up rolls are supported will tend to move down by gravity and by the nicely adjusted force of the spring acting on the lever 12, and thus will set the parts of the friction drive harder together, thus driving the rolls with more power to force the welt through.

The downward tendency of the pivoted arms carrying the take-up rolls, when a welt arrives and will not go through, is due to the fact that the fabric is lengthening and easing up between the take-up rolls and the needles during the time the welt remains be-

fore the take-up rolls and hence the pivoted arms with the rolls will tend to fall. In other words, when the take up rolls cease to perform their taking up action, due to an 5 obstruction arriving thereat, more power is applied at once by the spring and the weight of the parts, which then is allowed to act or rather become effective because the suspended relation of the rolls to the fabric or to the 10 needles has been disturbed. If now the rolls 15 are taking up the fabric too rapidly and placing too much tension therein, the rolls will tend to creep up on the fabric because of their pivoted supporting arms and this 20 will be against the pressure of the spring 12* which will therefore yield and allow the friction drive members to loosen up and thus 25 reduce the drive.

The device weighs on the fabric and controls the drive according as the excess tension 30 on the fabric tends to cause the rolls to rise by creeping up on the fabric or according as the rolls are not taking up fast enough, the latter result being also due often to welts. 35 If the rolls tend to move down as a body due to welts or decrease in tension the spring and weight of the parts act to give a more powerful driving action and if the rolls tend to move up bodily, due to increased tension the 40 drive will be reduced.

It will be understood, of course, that where I refer herein to the tendency of the rolls to move up or down, I do not mean that there is any appreciable movement of the rolls vertically because the friction driving surfaces 45 of the friction drive are in contact and the effect of the action of the parts under the varying tension of the fabric is rather to increase and decrease the pressure between the friction members to meet the requirements.

In the operation of the apparatus the rolls have a tendency to move down bodily under slackening of the fabric, this tendency causing 50 an increased pressure between the members of the drive. The spring and adjusting screw 23 enable the operator to change the stress of pressure to which the parts are subjected and thus the apparatus may be set 55 to suit different grades of yarns or different degrees of tension on the fabric. Of course the stress to which the rolls are subjected is due also to the fact that they have a tendency to gravitate.

55 I claim:-

1. In combination in a take-up for knitting machines, a pair of take-up rollers, a movable support therefor, driving means for the take-up rollers, including a clutch, and a 60 pivoted lever connected with the movable take-up support for controlling the clutch, substantially as described.

2. In combination in a take-up for knitting machines, a pair of take-up rollers, a 65 driving means therefor, including a clutch,

a movable support for the take-up rollers, and a connection between the said movable support and the clutch, including a pivoted lever and a link, substantially as described.

3. In combination in a take-up for knitting machines, a pair of take-up rollers, a movable support for the said rollers, a drive shaft, with means connecting the same with the rollers, including a clutch on the drive shaft and a connection for operating the clutch from the movable support of the take-up rollers, substantially as described. 70

4. In combination in a take-up for knitting machines, a pair of take-up rollers, a movable support for said rollers, a vertical 80 drive shaft, with connections therefrom to the rollers, including clutch members on the drive shaft and a lever connected to the movable support of the take-up rollers, and arranged to operate the clutch, substantially 85 as described.

5. In combination in a take-up for knitting machines, take-up rollers, a movable support therefor, worm gearing for driving the take-up rollers, a drive shaft extending 90 through the worm, clutch members on the drive shaft to connect the worm with said shaft, and a connection from the movable support of the take-up rolls for operating the clutch, substantially as described. 95

6. In combination in a take-up for knitting machines, a pair of take-up rollers, worm gearing for driving the same, a vertical shaft passing through the worm, a clutch for connecting the worm with the 100 said shaft, and a lever extending over the shaft and connected with the clutch for controlling the same, said lever being connected with the movable support of the take-up rolls, substantially as described. 105

7. In combination in a take-up for knitting machines, take-up rollers, a movable support therefor, worm gearing for driving the take-up rollers, a drive shaft extending through the worm, a clutch for connecting 110 the worm with the drive shaft, and a connection between the movable support of the take-up rollers and the said clutch, substantially as described.

8. In combination in a take-up for knitting machines, a pair of take-up rollers, a support therefor under stress or tendency to move, a worm and worm gear for operating the pair of rollers, a friction clutch for operating the worm, a spring for applying 115 pressure to the support and to the clutch and connections between the said support of the rollers and the spring and friction clutch whereby variations in the tension of the fabric control, through the said take-up rolls 120 and their support, the pressure between the members of the friction clutch, substantially 125 as described.

9. In combination in a take-up for knitting machines, a pair of take-up rollers, a 130

support therefor under stress or tendency to move, a friction clutch with means operated thereby for operating the rollers, a spring for applying pressure to the support and members of the friction clutch, and connecting means between the support and the spring and friction members, whereby variations in the tension of the fabric control, through the said take-up rolls and support, the pressure between the members of the friction clutch, substantially as described.

10. In combination with the take-up rollers of a knitting machine, a support for said rollers under stress or tendency to move, means for driving the rollers including a friction clutch, a lever with means for pressing the members of the clutch together, means of connection between said lever and the support of the take-up rollers and means for applying pressure to the friction clutch and support of the take-up rollers through the said lever, substantially as described.

11. In combination with the take-up rollers, of a knitting machine, a support for the rollers under stress or tendency to move, means for driving the rollers including a friction clutch, a lever, an adjustable device carried by the lever and communicating pressure to the members of the friction clutch means for applying tension to the lever and a connection between the take-up rollers' support and the said lever, substantially as described.

12. In combination with the take-up rollers of a knitting machine, means for driving the same including the intermeshing worm and worm wheel, a support for the rollers pivotally supported with the axis of the pivot passing substantially through the

intermeshing point of the worm and worm wheel, a friction clutch for driving the worm and means for controlling said clutch from the pivoted support of the take-up rollers, substantially as described.

13. In combination in a take-up for knitting machines, a pair of take-up rollers, a slotted shaft, a worm through which the shaft extends loosely, a worm wheel between the worm and take-up rollers, a friction clutch, one member of which is connected with the worm and the other member splined to the shaft, a movable support for the take-up rollers and means controlled thereby for pressing the splined member against the worm member, said means including the pin sliding in the upper end of the shaft and the key 18 extending through the slots in the shaft to engage the friction member, substantially as described.

14. In combination with the take up rollers of a knitting machine, a pivoted support therefor, intermeshing members for driving the said rollers, one of said members being carried on the pivoted support, said support having the axis of its pivot passing substantially through the intermeshing point of the said members, a clutch for driving the intermeshing members, and means for controlling the said clutch from the pivoted support of the take up rollers, substantially as described.

In testimony whereof, I affix my signature in presence of two witnesses.

GEORGE LAWSON BALLARD.
